UNITED STATES PATENT OFFICE.

ALEXANDER L. CLARK, OF PRINCETON, IOWA, ASSIGNOR OF ONE-HALF TO
PEARLY STILES AND HARVEY STILES, OF PRINCETON, IOWA.

BOILER-FEEDER.

SPECIFICATION forming part of Letters Patent No. 737,348, dated August 25, 1903.

Application filed October 11, 1902. Serial No. 126,898. (No model.)

To all whom it may concern:

Be it known that I, ALEXANDER L. CLARK, a citizen of the United States, residing at Princeton, county of Scott, and State of Iowa, have 5 invented a new and useful Boiler-Feeder, of which the following is a specification.

My invention is an improvement in automatic boiler-feeders, the object of the invention being to produce a device of this character which will be sensitive enough to respond promptly to the action of the water and steam in the boiler and which will be reliable in its operation, and a further object is to provide my improved attachment with audible and 15 visible signals, which will keep the engineer informed of the condition of the boiler and of the operations of the feeder.

In the accompanying drawings, Figure 1 is an elevation showing the application of my device, the boiler being shown in outline. Fig. 2 is a perspective view of my attachment. Fig. 3 is a vertical section taken centrally through the attachment, parts being shown in elevation. Fig. 4 is a section taken at a right angle to Fig. 3, the float being in elevation. Fig. 5 is a detail view, partly in section, on about the line 5 of Fig. 3. Fig. 6 is a horizontal section taken through one of the pivoted guide-blocks.

30 In the above-described figures, A represents a steam-boiler, A' the dome, and A² the pump supplying the boiler with water.

B represents a steam-pipe leading from the boiler to my attachment, and B' a steam-pipe 35 leading from my attachment to the pump.

B² is the pipe leading from the pump to the boiler.

In carrying out my improvement I employ a cylinder C, having in its upper portion a 40 lateral extension C'. In the cylinder is a hollow piston or float D, downwardly open. In the extension is a transverse shaft E, to which is pivotally secured the arm E', the said arm being bifurcated at its free end, as shown at

45 E². Arms D' extend upward from the piston, which is formed with a conical top, and between these arms is mounted an antifriction-roller D², which is engaged by the bifurcated arm E'. One end of the shaft E is journaled 50 in the wall of the part C', while the other passes through a suitable stuffing-box E³ and

carries a crank E⁴. Adjacent the stuffing-box a threaded opening is produced in the wall of the extension, and a perforated threaded sleeve E⁵, having a flange intermediate its ends, is secured in the opening, the inner side of the flange bearing against the outer wall of the extension. The outer end of the sleeve is concave, and the stuffing-box is threaded on the sleeve, bearing against the outer side of the flange. Any suitable packing material 55 may be employed in the stuffing-box.

The upper end of the crank E⁴ is pivoted to a guide-block F, Figs. 2 and 6, and through the guide-block runs a shaft F', having a hand-wheel F² at one end and threaded at the opposite end. At the threaded end of the shaft is a guide-block F³, threaded to correspond to the portion of the rod passing through it. This block is pivotally connected to a crank-arm F⁴. The portion of the rod passing through the block F has a groove F⁵ around it, into which projects a pin F⁶, preventing forward or rearward movement of the rod relative to this block. By means of the hand-wheel the crank-arms E⁴ and F⁴ can be adjusted 65 relative to each other.

The crank-arm F⁴ is connected to a valve-stem G, connected to a valve of the usual type located in the valve-chamber G'. A cam H 80 is carried by the arm F⁴. A whistle I is located at the upper end of a branch I' of the steam-pipe B, in which is the usual valve, (not shown,) the stem of which is connected by a link I² to a rod I³, the lower end of the rod 85 terminating in a shoe resting on the cam H. A guide-bracket I⁴ extends from the union of the pipes B and I, and between this bracket and the collar I⁵ is the spring I⁶. A water-gage J is attached to the cylinder C by the pipes J' J². From the top of the cylinder extends a pipe K, which leads to the upper part of the boiler, while from the lower part of the cylinder extends a pipe K', leading to the lower part of the boiler. 90

The operation of my device is as follows: Water from the boiler will enter the cylinder through the pipe K' and stand therein and in the gage J at the same level as in the boiler, lifting the piston D, which acts also as a float, 100 the arm E' being lifted, the bifurcated end traveling on the antifriction-roller turning the

rod E, throwing the crank-arm F in the direction of the arrows, Fig. 2, and drawing, by means of the shaft F', the crank-arm F⁴ in the same direction. This movement when the 5 rise in the water has reached a predetermined limit will close the valve in the chamber G, while the cam will force up the rod I³ and close the whistle-valve. As the water falls the movement will be reversed and the valve 10 in the chamber opened, the shoe will slip from the cam, and the whistle-valve will open, steam will pass from the boiler to the pump by way of the pipes B B', and the pump will be started and water supplied to the boiler 15 through the pipe B².

Having thus fully described my invention, what I claim as new, and desire to secure by Letters Patent, is—

1. In a boiler-feeder, the combination with 20 a boiler, and pump, a cylinder having communication with the boiler, a piston in said cylinder, an antifriction-roller mounted on the upper side of the piston, a shaft within the cylinder, an arm secured to the shaft at 25 one end and bifurcated at the other, the bifurcated portion engaging said roller, and means connected to the shaft for admitting steam to the pump when the piston falls.

2. In a device of the kind described, the 30 combination with a boiler, of a pump adapted to supply the boiler with water, a steam-pipe leading from the boiler to the pump, a valve in said pipe, a crank-arm attached to the stem of said valve, a cylinder attached to said boiler, 35 a shaft within the cylinder a crank-arm attached to the outer end of the shaft, a shaft

threaded at one end and carrying a hand-wheel at the other connecting the crank-arms, and means within the cylinder for actuating the crank-arms and opening the valve when 40 the water in the boiler falls below a predetermined limit.

3. In a device of the kind described, the combination with a boiler, a pump connected therewith, a steam-pipe running from the 45 boiler to the pump, a valve in said pipe, a branch pipe terminating in a whistle, a valve in said pipe, a crank-arm connected to the stem of the valve in the steam-pipe, a cam mounted thereon, a vertical rod terminating in a shoe 50 resting on said eccentric, a link connecting the stem of the whistle-valve with the rod, and automatic means for turning the crank-arm and opening both valves when the water in the boiler falls below a predetermined limit. 55

4. A device of the kind described comprising a cylindrical casing having a lateral extension in its upper portion, a float adapted to work in its lower portion, a bifurcated stem attached to the upper part of the float, a 60 roller mounted therein, a shaft journaled in the casing and passing through the extension, an arm secured thereto bifurcated at its inner end, the said roller being adapted to travel between said bifurcated portions, and 65 a valve adapted to be actuated by the rotation of said shaft as the float rises and falls.
